SCREW PROPELLER

Claude O. Kell, United States Navy

Application August 25, 1937, Serial No. 160,858

4 Claims. (Cl. 170—159)

(Granted under the act of March 3, 1883, as
amended April 30, 1928; 370 O. G. 757)

1

My invention relates to marine screw propellers, and more particularly to a propeller blade the back of which is of such a configuration as to delay or defer the development of back cavitation to increased blade velocities and the face of which, adjacent the leading edge, is shaped to minimize face cavitation.

As is well understood in connection with marine propellers the face of a blade is the driving face or that surface which propels the water astern when the propeller is in motion; while the back of the blade denotes the surface opposite the face. The different types of cavitation take their names from the sides of the propeller blade where they occur and hence are broadly classified as face cavitation and back cavitation.

Face cavitation generally starts at the root sections which is due in part to the thicker sections at the base of the blades. While this type of cavitation does not have a marked effect upon the efficiency of screw propellers throughout the range of normal operating slips, it is nevertheless objectionable since it is suspected as being the cause of erosion of the blade face and may be the source of objectionable and even serious vibrations. As will be pointed out more in detail hereinafter, face cavitation in accordance with my invention is minimized or substantially eliminated by setting back the blade face adjacent to the leading edge of the blade and at the root sections thereof.

Back cavitation, however, presents a far more serious problem in that when developed to a sufficient degree it reduces propeller thrust and therefore efficiency. Although this type of cavitation cannot be eliminated its occurrence or incidence can be deferred to increased blade velocities. Back cavitation is of two forms: First, that which initially appears as vortices off the blade tips and develops into leading edge cavitation with increase in tip speed and thrust; and second, that which first appears as bubbles forming on the following part of the blade back, which is that part of the back taken with reference to the maximum thickness of the blade sections. This form of cavitation is termed burbling cavitation as distinguished from the first form thereof, namely, leading edge cavitation.

Leading edge cavitation first appears as vortices passing off the blade tips and forming helices in the propeller wake. With increasing speed and thrust there is a corresponding development of these vortices until what appears to be an independent flow is formed across the blade tips, and bubbles appear down along the leading

edge of the blade. As the speed is further increased the width of the flow across the blade tips increases and the trailing edge of this flow passes off into the propeller wake as wider bands of vortices. The cavitation along the leading edge becomes wider and finally when well developed extends across the entire back of the blade as a part of the independent flow which began at the tip sections. This flow remains intact until it is well clear of the following edge of the blade. Soon after leading edge cavitation has developed into an independent flow, as described above, the efficiency of the propeller is found to be affected.

The second type of back cavitation, namely, burbling cavitation, forms on the trailing part of the blade considered with reference to the maximum thickness of the blade sections. At the first appearance of burbling type of back cavitation, separate and distinct bubbles are seen forming on the following half of the blade back. As far as is known at present, these bubbles after forming move in the stream of water flowing across the back of the blade and pass off into the wake of the propeller without collapsing on the blade back. With decrease of the cavitation index accomplished by increase in speed, with pressure constant, the area affected is found to expand both radially and across the width of the blade towards the maximum thickness of the blade. When completely developed most of the following part of the back of the blade is affected. But even in this stage of development the cavitation is confined to the following half of the blade. With but a slight decrease in the cavitation index after the first bubbles form, the efficiency of the propeller is affected.

From the discussion in the preceding two paragraphs it is clear that leading edge cavitation and burbling cavitation are functions of the cavitation index, increasing with a decreasing cavitation index accomplished by increase in speed, where the cavitation index is defined as the ratio

$$\frac{P_o}{q}$$

In this ratio, P_o is the absolute static pressure on any blade section and q is the kinetic energy of the water relative to the blade section at any given radius. The kinetic energy

$$q = \frac{m}{2} V_s^2$$

in which m is the mass of the water and V_s the relative velocity of flow to the propeller blade sections.

With a view to delaying or deferring back cavitation to increased blade velocities I have made an analysis of the factors entering into the phenomenon of water flow around sections at various radii of the propeller blades and have established empirically a relation between the cavitation index and the camber ratio,

$$\frac{c_r}{b}$$

where c_r is the maximum thickness of the blade section under consideration and b is the distance from the point of maximum thickness of the blade section under consideration to the trailing edge of the blade measured along the chord of the developed blade section. By means of this established relation between the cavitation index and camber ratio it is possible to determine the shape of the developed blade sections at the various radii, as will be pointed out more in detail hereinafter. The back cavitation, dependent upon the relation between the cavitation index and camber ratio, is only that part of the phenomenon that develops between the position of maximum thickness of the blade section and the trailing edge.

Blades, particularly those of marine propellers, are commonly designed with reference to developed sections of the blade. In forming a developed section, a section of the blade is cut at the desired radius by a cylinder concentric with the axis of the propeller and the cylinder then developed into a plane parallel with this axis. The blade section lying in the plane of the developed cylinder is a "developed section" and this term is to be understood as designating such a section in the specification and claims.

In the light of the foregoing, it is among the several objects of my invention to provide a blade adapted for movement through a liquid fluid medium in any developed section of which the camber ratio and cavitation index are related in a manner to delay or defer the development of back cavitation; to provide a blade of high efficiency; and to provide a blade wherein face cavitation is substantially eliminated or minimized.

Other objects and many of the attendant advantages of this invention will be readily appreciated as the same becomes better understood by reference to the following detailed description when considered in connection with the accompanying sheet of drawings, wherein:

Fig. 1 is a view of a developed section of my blade taken at any convenient radius; and

Fig. 2 is a view in elevation of the novel propeller blade of my invention on which the section of Fig. 1 is taken.

In order to formulate the equation which states empirically the relation that must exist between the cavitation index and the camber ratio if back cavitation is to be deferred, it is necessary that the following factors entering therein be considered:

Let P_A = atmospheric pressure.

P_w = pressure on blade section due to depth of water.

P_v = vapor tension of salt water.

m = mass density of sea water.

V_a = speed of advance, in feet per second, or that speed of the water at the position of the propeller, with reference to some point at an infinite distance.

C_s = increase of speed of water at the propeller disc due to suction of the propeller, or circulation of water around the blade section.

$\frac{C_a}{2}$ may be taken as a function of the slip, with sufficient accuracy.

V_s = speed of water relative to a point on the back of the blade.

c = the projected blade thickness at the axis of propeller, which is determined by blade thickness ratio or fraction.

c_r = maximum thickness of blade section at the radius under consideration.

b = the distance from the point of maximum thickness of the blade section under consideration to the trailing edge of the blade, measured along the chord of the blade section.

q = kinetic energy of water relative to the blade section at the given radius.

R = radius of propeller.

r = radius of blade section.

d = diameter of propeller at blade section.

N = revolutions per second.

A = a constant (to be explained below).

From theory, the relative velocity of water at a given blade section of a revolving propeller is defined by

$$V_s^2 = (\pi d N)^2 + \left(V_a + \frac{C_a}{2} \right)^2 \quad (1)$$

We further know from hydromechanics that

$$q = \frac{1}{2} \text{ mass} \times (\text{velocity})^2$$

$$\therefore q = \frac{m}{2} V_s^2 \quad (2)$$

The absolute static pressure on the blade section will be

$$P_o = P_A + P_w - P_v \quad (3)$$

The maximum thickness of the blade section under consideration is obtained by the equation

$$\frac{c_r}{c} = \frac{R - r}{R} \quad (4)$$

From a consideration of Equation 4 it should be clear that the maximum blade thickness of any section is proportional to the distance of the section from the blade tip.

From research work done by me I have determined that if back cavitation is to be delayed or deferred to higher blade velocities, a definite relation must exist between the cavitation index, P_o/q , and the camber ratio, c_r/b . This relationship is defined by the equation

$$\frac{P_o}{q} = A + K \frac{c_r}{b} \quad (5)$$

where A and K are coefficients that are fixed for any one blade. These coefficients, however, may vary within certain limits and still permit substantial attainment of the objects of this invention. The limits of variation are as follows:

Coefficient A ..... 0 to 0.035
Coefficient K ..... 3.750 to 4.167

By suitable computations, as will now be explained, and involving, among other things, the aforesaid Equations 4 and 5, the values of c_r , b and h for each developed blade section are established. The value h is the distance of the position of the greatest blade thickness from the leading edge of the blade section measured along the chord of the section. The computed values of c_r , b and h for the various sections are tabulated and then employed in subsequent graphical constructions of the various developed blade sections.

As a preliminary to any computation of these section values it is assumed that the following data are given. The curve of effective horse power of the ship for which the propeller is to be designed, that is, a curve of effective horse power plotted against the speed of the ship; the required revolutions of the propeller corresponding to the speeds of the ship; the wake factor or estimated value of the wake as a fraction of the ship's speed; the estimated thrust deduction at the different speeds of the ship; and the depth of submergence of the propeller shaft. The propeller diameter and pitch of the propeller in question are obtained by several well-known methods

of calculating these characteristics. From a consideration of the thrust to be developed by the propeller, a blade thickness fraction or ratio is assumed from experience which will give sufficient area at the base of the blades to provide ample strength and rigidity.

With the diameter of the propeller determined from the propulsion characteristics of the ship in question, the maximum blade thickness at the various blade sections may now be computed. By multiplying the blade thickness ratio with the diameter of the blade the value c_r , which is the projected blade thickness at the axis of the propeller, is determined. The different values of the maximum blade thicknesses, c_r , at the various sections are obtained by use of Equation 4 hereinbefore set forth.

The following procedure is adopted in computing the various values of b at the several blade sections. From average barometric pressures, an assumed temperature of sea water and draft of the ship, the value of P_o is determined by Equation 3. Knowing the required speed of revolution, N , for a given ship speed and the speed of advance V_a in feet per second, the relative speed V_s at any diameter d can be calculated by employing Equation 1. Having determined the relative velocity, V_s , the kinetic energy q is derived by the use of Equation 2. By combining the results of Equations 2 and 3, the cavitation index,

$$\frac{P_o}{q}$$

may be determined for the various blade sections. Substituting the various values of

$$\frac{P_o}{q}$$

in Equation 5 and solving with the proper values of A and K within the limits hereinbefore specified, the values of the camber ratio

$$\frac{c_r}{b}$$

are thereby obtained. Since c_r for the various blade sections has been obtained as previously pointed out, the value of b , the chord length from the position of maximum thickness to the trailing edge of the blade at the radius in question, is determined. It should be clear from the foregoing, that a value of b is determined for each blade section corresponding to the previously calculated values of c_r for the sections in question.

It now is only necessary to determine the remaining section dimension h so that the various developed blade sections may be graphically constructed. It will be remembered that h is the distance of the position of the greatest blade thickness from the leading edge of the blade section measured along chord of the section in question. Based on experimental results I have determined that h should bear a definite relation to b if highest efficiency is to be attained and the development of back cavitation deferred or delayed. The relation that must obtain between b and h is expressed by the following equation

$$\frac{b}{b+h} = 0.65 \quad (6)$$

By substituting the various values of b determined by the solution of Equation 5 in Equation 6, the necessary values of h corresponding to the different propeller blade sections are determined. Thus, the total chord length ($b+h$) for each of the blade sections is had.

From a tabulation of the values c_r , b and h for each blade section, developed blade sections are now graphically constructed in a manner to be explained. Referring now to Fig. 1 of the drawings, there is shown depicted therein a typical developed blade section, the construction of which is based on one set of values c_r , b and h . In carrying out the graphical construction the length FM equal to c_r is laid off perpendicular to the section chord EK , where EK is taken equal in length to $(b+h)$. It will thus be observed that the maximum blade thickness c_r has the point M on the section chord situated at a distance b from the trailing edge E of the blade and at a distance h from the leading edge K thereof. ME is now laid off in the manner shown equal to ME and a circular arc EFE' is struck through the points E , F , E' with the center of the arc lying along the line 3 which is an extension of the line FM . Any of the well known geometrical constructions may be employed in striking the arc EFE' . In a similar manner MK' is laid off equal to MK and the circular arc $K'FK$ struck with the center of the arc again lying along the line 3. Circular arcs EF and FK now form the back of the blade section $EMKE$. From a consideration of Equation 6, it is apparent that h will always be smaller than b so as to insure the attainment of a high blade efficiency. From this it necessarily follows that the radius of curvature of the circular arc FK will always be less than that of the arc EF and that the radius of curvature of the arc FK will be of such a value as to insure high blade efficiency. Thus, the developed blade section at any radius will have the back portion thereof between the point of maximum thickness F and the trailing edge E lying substantially along a circular arc; and the camber ratio of this back portion will be related to the cavitation index in a manner to delay the development of back cavitation. Only that part of the phenomenon of back cavitation that develops between the point of maximum thickness F and the trailing edge E is controlled by the relation between the cavitation index and the camber ratio as set forth in Equation 5, supra.

As a result of my research work I have determined that face cavitation or cavitation on the face of the blade adjacent the leading edge thereof can be eliminated or greatly reduced by setting back the face of the blade adjacent the leading edge. The characteristics of this correction are dependent on the relative speed V_s and the slip at which the propeller is operating. The face adjacent the leading edge is set back, beginning a short distance back from the leading edge by striking a circular arc MG , the center of which is likewise situated on the line 3. Generally, this face correction is found necessary only on the root sections of the blade. By setting back the face of the blade adjacent the leading edge in the manner shown in Fig. 1 of the drawings the final blade section $EMGF$ is obtained.

Having determined the shapes of the developed blade sections at the different radii, as outlined above, the strength of the blade is investigated. If the results indicate that any change in sections is necessary, the blade thickness fraction or ratio is corrected accordingly, new section characteristics are computed and the graphical constructions based thereon then carried out all as described hereinbefore.

According to the provisions of the patent statutes I have set forth the principle and mode of operation of my invention and have illustrated and described what I now consider to rep-

resent its best embodiment. However, I desire to have it understood that within the scope of the appended claims the invention may be practiced otherwise than as specifically illustrated and described.

The invention herein described and claimed may be used and/or manufactured by or for the Government of the United States of America for governmental purposes without the payment of any royalties thereon or therefor.

I claim:

1. A blade adapted for movement in a liquid fluid medium, said blade having a back which in any developed section of the blade has that portion thereof between its point of maximum thickness and the trailing edge lying substantially along a circular arc, the camber ratio of this back portion being related to the cavitation index according to the equation

$$\frac{P_o}{q} = A + K \frac{c_r}{b}$$

where A and K are coefficients that are fixed for any one blade but which may vary respectively from 0 to 0.035 and from 3.750 to 4.167.

2. A blade adapted for movement in a liquid fluid medium, said blade having a back which in any developed section of the blade has that portion thereof between its point of maximum thickness and the trailing edge lying substantially along a circular arc, the camber ratio of this back portion being related to the cavitation index according to the equation

$$\frac{P_o}{q} = A + K \frac{c_r}{b}$$

where A and K are coefficients that are fixed for any one blade but which may vary respectively from 0 to 0.035 and from 3.750 to 4.167, and the distances h and b respectively of the leading and trailing edges measured along the chord of any section from a point thereon corresponding to the maximum blade thickness being related according to the equation

$$\frac{b}{b+h} = 0.65$$

3. A blade adapted for movement in a liquid fluid medium, said blade having a back which in any developed section of the blade has that portion thereof between its point of maximum thickness and the trailing edge lying substantially along a circular arc and the remaining portion thereof between said point of maximum thickness

and the leading edge lying along a circular arc the radius of curvature of which is less than that of the first mentioned arc and of such a value as to insure high blade efficiency, the camber ratio of the first mentioned back portion being related to the cavitation index according to the equation

$$\frac{P_o}{q} = A + K \frac{c_r}{b}$$

10 where A and K are coefficients that are fixed for any one blade but which may vary respectively from 0 to 0.035 and from 3.750 to 4.167.

4. A blade adapted for movement in a liquid fluid medium, said blade having a back which in any developed section of the blade has that portion thereof between its point of maximum thickness and the trailing edge lying substantially along a circular arc, the camber ratio of this back portion being related to the cavitation index according to the equation

$$\frac{P_o}{q} = A + K \frac{c_r}{b}$$

where A and K are coefficients that are fixed for any one blade but which may vary respectively from 0 to 0.035 and from 3.750 to 4.167, and the maximum blade thickness of any section being proportional to the distance of the section from the blade tip.
